UNITED STATES PATENT OFFICE

1,996,541

REVERSIBLE SIGN

Charles A. Fetters, Washington, D. C.

Application June 11, 1934, Serial No. 730,105

11 Claims. (Cl. 40—64)

The invention relates to reversible signs and has for its object to provide a device of this character comprising a sign body formed from a plurality of sections or panels pivoted together on a vertical pivotal axis and adapted to be reversed for changing the display indicia thereon as desired. Also to obviate the use of hollow channels at the upper and lower edges of the sections, thereby simplifying the construction and allowing the device to be cheaply manufactured and sold.

A further object is to provide the hanging sign sections with angularly disposed flanges at their adjacent sides and interengaged non-round dished portions carried by the flanges and pivoted together and forming means for maintaining the sign sections in the same vertical plane as the sign upon reversing any of the sections, and also to space the bottoms of the dished portions apart whereby sufficient spring action will be provided for allowing the reversing operation.

A further object is to reinforce the flanges of the sign sections by folding the same onto each other, thereby providing slide receiving means.

A further object is to provide a hanging sign comprising a plurality of reversible pivotally connected sections, pivoted on a vertical central axis and one of the edges of each sign section with a horizontal flange extending beyond opposite sides of the sections and bent upon itself and having a longitudinal groove in which the adjacent portions of adjacent sign sections are received and are held in the plane of the sign upon the reversal of any of the sign sections.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a perspective view of a hanging sign.

Figure 2 is a vertical transverse sectional view taken on line 2—2 of Figure 1.

Figure 3 is a detail perspective view of the interengaging pivotal means between the sign sections.

Figure 4 is a vertical longitudinal sectional view through adjacent engaging flanges of the sign sections showing the pivotal connection therebetween.

Figure 5 is a perspective view of a modified form of sign for the reception of slides.

Figure 6 is a perspective view of the pivotal connection between the sign sections shown in Figure 5.

Figure 7 is a vertical transverse sectional view through one of the pivotal connections taken on line 7—7 of Figure 5.

Figure 8 is a perspective view of a further modified form of hanging sign.

Figure 9 is a vertical transverse sectional view taken on line 9—9 of Figure 8.

Figure 10 is a horizontal sectional view taken on line 10—10 of Figure 8.

Referring to the drawings, and particularly to Figures 1 to 4 inclusive, the numeral 1 designates a plurality of sign sections which form a hanging sign adapted to be supported by a member 2 from any suitable support. This sign is of the type generally set forth in my Patent No. 1,478,511, issued December 25, 1923, and is particularly adapted for use in ice cream parlors or any place where a list of items are shown, any of which items may become exhausted from stock, and at which time a particular sign section may be reversed for displaying different indicia. Each sign section 2, at its upper and lower edges, is provided with horizontally disposed flanges 3 and 4 which form a double function, that is they form a connecting means between the sign sections and also stiffening means for the sections, which is particularly desirable when the sign sections are being reversed.

The sign sections 1 are pivotally connected together on a vertical axis and on rivets 5, which extend through the flanges 3 and 4 of adjacent sign sections. The flanges 3 and 4 are provided with elongated or off-round struck down portions 6, and through which the pivot rivets 5 extend. It will be noted that the struck down portions 6 are in spaced relation as shown in Figure 4 and in a nesting relation when the sign sections are in the same vertical plane, and being in spaced relation, as one sign section is rotated, the struck down portion 6 will flex thereby allowing the upper struck down portion to move out of position within the other and to spring back into the other after the completion of the rotation of the sign section. By making the struck down portions 6 off-round and nesting only when the sign sections are in the same plane, it is obvious that when they are in interengagement the sections will be positively held in the same vertical plane. It will be noted that the struck down portions have bevelled engaging surfaces 7 as clearly shown in Figure 4, hence they will cam out of nesting relation during the rotation of sections 55

in relation to each other. By placing the interengaging struck down portions 6 at the pivotal points of the sections 1, it will be obvious that they can be easily disengaged by the operator 5 grasping the outer end of a particular section and rotating the sections as there will be a relatively long leverage on the interengaging point, hence danger of bending the sign is obviated, as is the difficulty with devices at present constructed. If 10 desired insertable slides 8 may be provided for the sign for increasing the range of indicia display on the sign, or for special sales.

Referring to Figures 5, 6, and 7 wherein the removable slide 8 is shown, the operation and use 15 of this form is substantially the same as that shown in Figure 1 with the exception of the use of slides 8. In this form the section flanges 3a and 4a are provided with turned flanges 9, which extend towards the body of the sign sections 1 and terminate short thereof so as to receive the inwardly and outwardly extending flanges 10 of the slides 8, hence it will be seen that the slides may be longitudinally inserted, otherwise the operation and construction is the 20 same as shown in Figure 1.

Referring to Figures 8, 9 and 10, in this form the operation is substantially the same as in the other forms, however it varies in construction. In this form the upper ends of the sign sections 1a 30 are provided with channelled flanges 10 which extend beyond the front and rear faces of the sections and are formed by bending the upper ends of the sections to the front side of the sections to form the flanges 11, and then bending the material at 12 onto the flanges 11 and extending beyond the rear of the sections with the longitudinal bend 13 forming a channel, in which the bottom edges 14 of the sections spring, and are held after a reversing operation. It will be noted 40 that the bottom edges 14 are provided with stiffening flanges 15 bent on the rear sides of the section and with outwardly struck portions 16 forming chambers 17, through the bottoms of which the pivot rivets 18 extend, therefore it will be seen that the rivets are concealed from view 45 and a flat portion 19 provided through which the rivets extend.

From the above it will be seen that a hanging reversible sign is provided which is simple in construction, the parts reduced to a minimum, and one wherein the pivot rivets extend through interengaged off-round portions of the sign sections 50 which interengaged portions maintain the sign sections in the same vertical plane when they are rotated. It will also be seen by referring to Figures 5 and 7 that when the sign sections are rotated, the slides 8 on the rear sides thereof will assume a position in the same plane as the sign sections thereby maintaining the same general 55 appearance of the front side of the sign after a reversing operation.

The invention having been set forth what is claimed as new and useful is:

1. A reversible hanging sign comprising a plurality of pivotally connected sections, flanges carried by the adjacent engaging sides of the sections, said flanges having pivot means extending therethrough on a vertical axis and means carried 60 by the flanges and surrounding the pivot means and forming means whereby the sign sections will be maintained in the same vertical plane upon reversing of the sign sections.

2. The combination with a reversible hanging sign having engaging flanges extending rear-

wardly from the upper and lower edges thereof, the flanges of adjacent sections engaging each other, vertical pivot members extending through the engaging flanges on the same vertical axis, of interengaging means between the engaging flanges and surrounding the pivot means and forming means whereby when any of the sections are reversed the sign sections will be maintained in the same vertical plane.

3. A device as set forth in claim 2 wherein the interengaging means comprises members struck from the engaging flanges and in nesting relation.

4. A device as set forth in claim 2 wherein the interengaging means between the flanges comprises integral struck out members having chambers with bottoms in nesting relation with their bottoms in spaced relation whereby said bottoms may flex upon initial and final rotation of a section for releasing the rotated section and for holding the rotated section in the plane of the sign after a rotation thereof.

5. A device as set forth in claim 2 including struck out nested interengaging means around the pivotal means and means carried by the flanges for receiving slides.

6. A hanging sign comprising a plurality of reversible sections, engaging flanges carried by the engaging edges of the sign sections, registering nested struck out portions carried by the engaging flanges and with their bottoms in spaced relation and a pivot member extending through said nesting member bottoms centrally thereof.

7. A device as set forth in claim 6 wherein the nested struck out members are off-round in shape.

8. A reversible sign comprising a plurality of pivotally connected reversible sign sections, the adjacent edges of the sign sections being provided with engaging outwardly extending flanges on one side of the sign sections, pivotal connections between said flanges out of the plane of the sign sections, the outer ends of the flanges terminating in inwardly extending flanges engaging the inner sides thereof, said last named flanges forming slide receiving means and slides in said slide receiving means.

9. A device as set forth in claim 8 wherein the slides are in the plane of the outer ends of the flanges and means carried by the slides and cooperating with the inner edges of the inwardly extending flanges for holding the slides in position.

10. A device as set forth in claim 8 wherein the slides are in the plane of the outer edges of the flanges and the pivotal means between the sections intermediate the signs and the slides whereby when the sign sections are rotated the slides will be in the plane of the sign sections.

11. A reversible sign comprising a plurality of reversible sign sections in a vertical plane, the upper edges of the sign sections having flanges extending forwardly to the forward side of the sections and then bent upon themselves and extending rearwardly of the sections and having longitudinal channels therein, the lower ends of the sections being disposed in the channels of the upper ends of the sections, said lower ends of the sections being bent upon themselves to reinforce the same, chambers formed in said bent portions of the lower ends of the sections and pivot members extending through said chambers and flanges of the upper ends of adjacent sections.
